JENTJE MULDER, OF DETROIT, MICHIGAN

DRAIN-PIPE FITTING

Application filed February 15, 1929. Serial No. 340,064.

This invention relates to drain pipe fittings and has a particular application to drain pipes of kitchen sinks.

One object of the invention is to provide a convenient means for quickly flushing out the trap of a drain pipe when desired.

Another object is to provide a flushing connection to a drain pipe from a water supply pipe and to establish such connection through 10 a fitting having a container therein adapted to receive a cleansing compound and to deliver such compound at a suitable predetermined rate to such water as may be delivered through the fitting for flushing purposes.

Still another object is to provide such a fitting with a valve controlling the connection with the sink (or other source of drainage water) so that said valve may be closed during a flushing operation and conserve such flushing pressure as might otherwise be wasted by a flow of the flushing water to the sink or other vessel to be drained.

A further object is to adapt such a valve member to also serve, when desired, merely as 25 a drain pipe closure, permitting a desired level of water to be maintained in the sink or other vessel from which the drain pipe leads.

A still further object is to provide for convenient control of the drainage flow valve member and of the flushing valve without requiring the operator to reach under the sink.

These and various other objects the invention attains by the construction hereinafter described and illustrated in the accompanying 35 drawings, wherein:—

Figure 1 is a view in front elevation of a sink having its drain pipe trap adapted to be flushed in accordance with the invention.

Figure 2 is a side view of the same, with 40 certain parts in section.

Figure 3 is a top plan view of the fitting through which a flushing connection to the drain pipe is established.

Figure 4 is a vertical sectional view of said fitting, taken upon the line 4—4 of Figure 3.

Figure 5 is a sectional detail taken on the line 5—5 of Figure 1.

In these views, the reference character 1 designates a sink of the usual kitchen type, 50 having the usual faucets 2 thereabove for de-

livering hot and cold water from supply pipes 3, in which pressure is maintained.

The usual drain pipe 4, opening downwardly from the sink is equipped with the customary trap 5 to retain any heavy objects that pass into the drain pipe and to establish a water seal against upward flow of sewer gases.

The present invention comprises a hollow fitting 6, having aligned openings 7 and 8 in its top and bottom, adapting it to be connected to the drain pipe 4, above the trap 5. While said fitting may be variously formed, it preferably has the nature of a metallic casting, with its top 9 bolted or otherwise removably connected to the body thereof. A connection 10 to said fitting from one of the pipes 3 is controlled by an ordinary valve 11, so that upon opening said valve, water under pressure is supplied to the fitting for the primary purpose of flushing out the trap 5. In order that the flushing water thus admitted may act effectively to clean out the trap, it is necessary to maintain such water at substantially its original pressure as it enters the trap. Therefore the drain pipe connection from the fitting 6 to the sink should be closed during a flushing operation. To accomplish this, a flap valve 12 is pivoted, as indicated at 13, in the upper portion of the fitting upon a bracket 13^a carried by the cover 9, so that when swung from its normal open position shown in dash lines in Figure 4 to the raised position shown in full lines in said figure, said valve seats against the top of the fitting and closes the opening 7 to the drain pipe. Preferably the seating face of the valve 12 is lined with rubber 14 or the like to better adapt it to form a water-tight closure.

To adapt the flushing water to act most effectively upon any grease or sediment accumulated in the trap 5, it is desirable to mix with such water a suitable quantity of some cleaning compound or detergent, that will cut the grease and act to loosen other dirt. The invention provides for readily accomplishing this result by removably mounting in the fitting 6 a container 15 for a cleaning compound which container is adapted to dispense the compound at a suit-

able rate to the flushing water, when the valve 11 is opened, by perforating the lower portion of said container, as indicated at 16, and disposing the portion so perforated directly opposite to the flushing water inlet, so that the pressure of such water will act upon the contents of the container through said perforations. As illustrated, the container 15 is of cylindrical form, and has its upper 5 end permanently closed and flanged to seat upon a packing ring 17 to form a water seal with the top of the fitting 6. Adjacent to its top said container is exteriorly threaded as indicated at 18, for detachable connection 10 with the fitting top. A filling opening 19 in the upper portion on the container wall, (best seen in Figure 4) is adapted to be normally closed by a sleeve 20, slideable and rotative on the container and limited in its 15 sliding and rotation by engagement of a pin 21, rigidly exteriorly carried by the container in a vertically elongated slot 22 of said sleeve, which slot has at its lower end a lateral extension 23 for receiving said pin to hold the sleeve normally in the position closing the 20 opening 19, as shown in Figure 4.

Preferably a partition 24 extends from wall to wall of the fitting 6 below the pivot axis of the valve member 12 so as to trap a 25 quantity of water in that portion of the fitting which receives the perforated part of the container 15, thus tending to maintain a water-saturated condition of the contents of said container.

30 An operating rod 25 for the valve 11 is suitably connected to the latter, as by an arm 25^a and extends forwardly and upwardly from said valve to project freely at its upper end through a supporting plate 26 preferably formed of sheet metal and attached to and depending from a board 27 covering the front of the sink.

To control the valve 12, a rock shaft 28 is journaled in a side wall of the fitting 6 and 35 carries arms 28^a and 28^b respectively inside and outside of said fitting. The arm 28^a is bent so as to bear freely upon the valve 12 to raise the latter to closed position by rocking said shaft. The arm 28^b has a suitable 40 pivotal connection to a control rod 29 which projects forwardly and upwardly, similarly to the rod 25 to freely pass through a slot 29^a in the plate 26.

The rod 26 preferably has a shoulder 30 near its front end, which may be engaged with the front of the plate 26 to adapt the valve 12 to be firmly held in closed position.

In the use of the described device, when it 35 is desired to flush out the trap, it is necessary only to first close the valve 12 by pulling upwardly on the rod 29 and then engaging the shoulder 30 with the plate 26. When the valve 12 is thus secured in closed position, the rod 25 is drawn upward, opening the 40 valve 11. The flushing water which is now

admitted to the fitting 6 has no outlet except through the trap 5 and consequently acts under full pressure upon any accumulation of sediment, dirt, or grease in said trap. The effectiveness of this action will be materially increased by the cleaning compound which will be progressively washed out of the container 15 through the perforations thereof, so long as the flushing is continued.

It is to be noted that the valve 12 may 45 be employed if desired, independently of the valve 11, to shut off the discharge of water from the sink, when it is desired to maintain the latter filled or partly filled with water.

While it will be apparent that the illustrated embodiment of my invention herein disclosed is well calculated to adequately fulfill the objects and advantages primarily stated, it is to be understood that the invention is susceptible to variation, modification and change within the spirit and scope 50 of the subjoined claims.

What I claim is:

1. In a device of the character described, the combination with a hollow fitting having 55 an inlet and outlet for connection with a drain pipe, of means for delivering a flushing liquid under pressure to said fitting, control means for such liquid delivery, a valve member in said fitting adapted to close said drainage inlet, means for manually actuating said valve member and for holding it in closed position, and means within said fitting for delivering a cleansing compound to the flushing liquid responsive to the pressure of its flow. 60

2. In a device of the character described, the combination with a hollow fitting having an inlet and outlet for connection with a drain pipe, of means for delivering a flushing liquid under pressure to said fitting, control 65 means for such liquid delivery, a valve member in said fitting adapted to close said drainage inlet, means for manually actuating said valve member and for holding it in closed position, and a container for a cleansing compound removably positioned in said fitting and adapted to dispense its contents to the flushing liquid responsive to the pressure of said liquid. 70

3. In a device of the character described, the combination with a hollow fitting having an inlet in its top and an outlet at its bottom providing for the drainage of a liquid through said fitting, and having an additional opening in its top, a container for a cleansing compound insertable in said fitting through said additional opening and adapted to close said opening when so inserted, said container having a perforated portion within the fitting, means for discharging a flushing liquid into said fitting against the perforated portion of said container, control means for such discharge, and a closure within said fitting adjustable to close said drainage inlet. 75

4. In a device of the character described, a

combination with a hollow fitting having an inlet and an outlet for connection with a drain pipe of a valve member within said fitting for closing said inlet, means exteriorly carried by said fitting for controlling said valve member, said fitting having in its lower portion a liquid trap, a container for a cleansing compound removably carried by said fitting and having a perforated portion depending within said trap, said trap having an inlet thereto for a flushing liquid.

5. In a device of the character described, the combination with a hollow fitting having its top formed with a collar projecting above said top for connection with a drain pipe and projecting also below said top, a valve member seating against said collar to close said inlet, means exteriorly carried by said fitting for controlling said valve member, said fitting having a drainage outlet and further having an opening for delivery to said fitting of a flushing liquid.

6. In a device of the character described, a hollow fitting having a drainage passage extended between its upper and lower ends and formed at one side of said passage with a chamber opening into said passage and having in its lower portion a liquid trap, and a container for the cleansing compound removably carried by the top of said fitting and depending within said chamber, and having a perforated lower portion normally occupying said trap, said fitting having an inlet for a flushing liquid opening into said trap.

35 In testimony whereof I sign this specification.

JENTJE MULDER.
